UNITED STATES PATENT OFFICE.

JOHN N. THORNTON, OF JERSEY CITY, NEW JERSEY, ASSIGNEE, BY MESME ASSIGNMENTS, TO UNDERWOOD COMPUTING MACHINE COMPANY, OF NEW YORK, N. Y., A CORPORATION OF NEW YORK.

COMBINED TYPE-WRITING AND COMPUTING MACHINE.

1,287,520.

Specification of Letters Patent. Patented Dec. 10, 1918.

Application filed April 17, 1912. Serial No. 761,674.

To all whom it may concern:

Be it known that I, JOHN N. THORNTON, a citizen of the United States, residing in Jersey City, in the county of Hudson and State of New Jersey, have invented certain new and useful Improvements in Combined Type-Writing and Computing Machines, of which the following is a specification.

This invention relates to a combined type-writing and computing machine of the Underwood-Hanson type, and more especially to means for readily adjusting the denominational column selector so that the computing columns will agree in denomination with the typewritten columns.

In this type of machine, all the digits of a number to be computed are first registered or set up in a nest of pins which determine the extent of movement of rack bars on which they are located, and then the computation is run up on a series of computing wheels, one for each set of rack bars, by means of a general operator which engages the set-up pins. To set the pins, coördinate or cross selection is utilized by giving each numeral key a linkage capable of setting any one of a series of pins arranged in a cross line, one on each of the several rack bars, the rack bars being moved *seriatim* out of register with their fellows, so as to enable a pin corresponding to the particular numeral key actuated to be set up when the column corresponding to this rack bar is being written in on the work-sheet on the typewriter carriage.

To accomplish the above, one or more selecting tappets are provided on the carriage, which come individually into successive engagement with a series of jacks connected individually to the several rack bars so as to move them *seriatim* out of register with their fellows during the step-by-step movement of the carriage. Each selecting tappet is made adjustable along the carriage so that when the position of the computing column as written on the work-sheet on the carriage is varied, the computing period or zone may be varied at the same time, enabling the computing mechanism to be concomitantly actuated in a new position of the computing column. When a column to be computed is located at any particular point in the written line, in order that it may be quickly reached in the actual operation

of typewriting a tabulating stop is also 55 adjusted on the typewriter carriage, so that by merely depressing a tabulating key, the carriage may be brought to the computing column without any unnecessary back-and-forth shifting of the carriage.

To adjust the tabulating stop for any position of a computing column, it is merely necessary to adjust the carriage to the point desired, and then read on the front scale the point at which the printing point is located and put the tabulating stop in the space on the rack on the carriage corresponding to this point by reference to the rear scale on the carriage.

Inasmuch as the tappet for controlling the 70 action of the jacks and thus the denominational columns of the computing mechanism is not located exactly in register with the tabulating stop, it generally requires some back-and-forth shifting and trying before 75 the correct location can be obtained. It is, therefore, the purpose of this invention to form a means for readily adjusting the position of the denominational column-selecting tappet without any unnecessary back-and-forth manipulating and trying. To accomplish this, the tappet, which is normally held in a depressed position by a universal retaining bar, can be raised to an elevated position such that it will engage in a position-finding notch provided in the frame bearing the series of jacks. This notch is so located that when the column-selecting tappet rests therein and the carriage is positioned for the column desired, the tappet 80 will be in proper position for actuating the column jacks to correspond with the particular column typewritten on the carriage.

Other features and advantages will hereinafter appear.

In the accompanying drawings—

Figure 1 is a diagrammatic top plan view slightly distorted to bring out the relative arrangement of parts concealed under other elements.

Fig. 2 is a vertical section taken from front to rear of the machine, with parts broken away to show the underlying structure.

Fig. 3 is a detail top plan view showing 105 the relation of the selecting tappet to its supporting bars and to the column jacks.

Fig. 4 is an enlarged detail view showing

the tappet in its normal position ready to go into register with the several jacks.

Fig. 5 is a view similar to Fig. 4, with the exception that the tappet is raised and located in the position-finding notch.

Fig. 6 is a detail perspective view showing the universal retaining frame which holds the tappet or tappets in their normal position.

Referring more particularly to the separate parts of this invention as embodied in the form shown in the drawings, 1 indicates numeral keys and 2 alphabet keys, which are mounted on key-levers 3 and engage bell cranks 4 to rock the same and thus swing type-bars 5 up rearwardly against the front side of a platen 6 mounted to rotate on a carriage 7. The carriage 7 is arranged to travel step by step at the actuation of any of the keys 1 or 2, under the control of an escapement mechanism indicated in general at 8. This escapement mechanism includes a rack bar 9 swingingly mounted on the carriage 7 by means of arms 10. The rack bar 9 engages a pinion 11 controlled in its rotation by an escapement wheel 12, which in turn is controlled by fixed and movable dogs 13 oscillated at each operation of a character key through the intermediary of a universal frame 14, which is engaged by heels 15 on the type-bars 5.

The carriage 7 not only has a step-by-step movement, but for the purpose of positioning the same for different zones of the worksheet, it may be given a jump or tabulating movement. For this purpose, there is provided a series of tabulating keys 16, mounted on key-levers 17 which are pivoted intermediate their ends and support at their rear ends, plungers 18 arranged to be projected up at the actuation of one of the keys 16, into the path of stops 19. The stops 19 are adjustably mounted on a rack 20 carried by the carriage 7 and determine by their position, the particular zone at which the carriage 7 will stop. The plungers 18, of which there may be a number corresponding to the number of tabulating keys 16, determine the exact denominational column or letter-space in any particular zone at which the carriage will stop for a given one of the stops 19. When any one of the plungers 18 is raised by its associated tabulating keys 16, it rocks a universal frame lever 21, which engages in a notch 22 provided in each of the plungers 18, and in turn pulls down on a link 23 to rock a lever 24 bearing at its forward end a contact roller 25, which underlies the rack bar 9 and is arranged to raise the same out of engagement with the pinion 11 at the actuation of any of the tabulating keys 16.

In addition to actuating the type-bars 5, the numeral keys 1 also actuate pin-setting mechanism, indicated in general at 26 to accumulate numbers corresponding to the par-

ticular numeral keys actuated. For this purpose, each numeral key is provided with a depending thrust link 27, which rocks an associated shaft 28 carrying a linkage 29. There is a series of these linkages corresponding to the series of numeral keys 1, and they are arranged in superposed relation to a cross row of pins 30, so that they can set any one of the pins in the cross row when the associated bar 31 on which the pin is mounted, is raised above its fellows.

Each of the bars 31 carries nine pins corresponding to the numerals "1" to "9", and these pins are settable from a position projecting above the bars to a position projecting below the bars where they extend into the path of a cross-bar 32 on a general operator 33, which may be actuated through interconnected gearing 34 from any suitable source of power indicated by the handle 35. The bar 32 engages whatever pins 30 are set up on the several pin-bars 31, so as to move them forward variable distances corresponding to the particular pins set, whereby computing wheels 36, one for each of the bars 31, are rotated a corresponding amount. The connection in this instance is shown to be made by a pinion 37 secured to each of the computing wheels 36, and a rack 38 formed on each of the bars 31. The computing wheels in this instance, are also in the form of dial wheels having numbers inscribed on their outer periphery, so that they can exhibit the same and thus show the particular digits which have been run up thereon.

In order to raise the rack-bars 21 individually to enable the setting of pins thereon, there is mounted on the carriage 7, so as to travel therewith, one or more selecting tappets 39 according to the number of computing columns desired. In this instance, only one selecting tappet is shown, although many more might be used. The selecting tappet 39 carries thereon a camming dog 40, which is arranged to engage one by one, during the step-by-step movement of the carriage 7, a series of jacks 41 pivotally mounted intermediate their ends on a frame 42, which is co-extensive with the frame of the typewriter. The camming dog 40 is arranged to raise the jacks 41 solely during the letter-feeding or forward movement of the carriage 7, and has an inclined surface 43 for gradually camming the jacks 41 upwardly at their front ends. During the return movement of the carriage, the camming dog 40 will yield backwardly against the tension of a spring 44, without actuating the jacks 41, it being pivotally mounted on the body of the tappet 39 for this purpose.

Each of the jacks 41 overlies, at its rear end, a thrust rod 45, which is connected at its bottom end to a corresponding transposition linkage 46, which is connected to raise

one of the pin-bearing bars 31. The transition linkages 46 are such that the jacks 41 while operated from right to left *seriatim* will raise the pin-bars 31 from left to right in succession.

It is not always desired, even when a number of selecting tappets 39 are used, to have the computing columns in the same location. Hence, it is necessary to adjust the position 10 of the tappet 39 when the corresponding computing column is changed in its location along the typewriting line on the work-sheet. For this purpose, supporting bars 15 47 and 48 are provided for the tappets 39 along which they may be adjusted. The supporting bars 47 and 48 are mounted on the auxiliary frame 49, which in turn is mounted on the carriage 7 and arranged to travel therewith.

20 The rear end of the tappet 39 is provided with a cylindrical or tubular opening 50, so that the supporting bar 47 can be threaded therethrough and maintain the tappet thereon while not interfering with the adjustment 25 of the tappet therealong. Any position of the tappet 39 on the bar 47 is determined by a pin 51, which extends in any one of a series of grooves 52 formed along 30 one side of the bar 47 and forming teeth therebetween. These grooves are arranged circumferentially and communicate with a surface groove 53 extending longitudinally of the bar 47, so that when the tappet 39 is swung to a position slightly higher than 35 that shown in Fig. 5, the tappet can be adjusted longitudinally of the bar 47.

The bar 48 is also provided with means for engaging the tappet 39 and holding the front end rigid against lateral movement 40 when once placed in any definite position along the carriage. For this purpose, the bar 48 is provided with a rack 54, between the teeth of which a rib 55 on the tappet 39 is arranged to engage.

45 It will be noted that the tappet 39 can be entirely detached from the bars 47 and 48, by being swung up to a position slightly higher than that shown in Fig. 5 and moved toward the end of the bar 47, the 50 bar 47 being reduced at both ends, as at 56, so as to permit such detaching movement by passing the reduced portion of the bar through a slot 57 communicating with the opening 50. The reduced ends 56 of the bar 55 47 may be threaded, as indicated in Fig. 6, to enable the mounting of the bar on the auxiliary frame 49 by means of plates 58. This threaded portion may also enable the 60 adjustment therealong of sleeved nuts 59, which extend through side plates 60 of a universal frame 61 and form pivotal mountings therefor.

This universal frame 61 includes a universal cross bar 62, which is arranged to 65 overlie the tappets 39 and return them from

an abnormal raised position, such as shown in Fig. 5 to a normal depressed position, such as shown in Fig. 4. The downward motion of the universal bar 62 is limited, however, by stop pins 63, which engage 70 notches 64 in the side plates 60. This is to prevent the burden of the universal frame from resting and pressing on the tappets 39 when in their normal working position. The universal frame 61 is held in its normal position resting on the stop pins 63, by means of springs 65 spirally wound around the sleeved nuts 59 and engaging the pins 63 at one end and a cross bar 66 of the universal frame 61 at their other end. 75 80

Mounted on each of the tappets 39, there is provided a conical cam roller 67, which may have certain functions, such as raising the tappet for action, which functions, however, are not pertinent to this particular invention. In this instance, the cam roller 67, when it is desired to locate the tappet for a particular column, is raised to the Fig. 5 position and dropped into a position-finding notch 68 provided in a top plate 69 of 90 the frame 42, which incloses and supports the denominational jacks 41. The position-finding notch 68 is cam-formed so that when the carriage is traversed in one direction or the other, the roller 67 will readily 95 ride out of the same and drop to its normal position under the urgency of the springs 65 after it has passed beyond the limits of the top plate 69.

The device may be used in several ways for 100 the purpose of locating a computing column at any point of the typewritten line. In thus locating the computing column, it is convenient to take some particular point in the typewritten column as a reference point, and 105 usually the decimal point is chosen, although this is purely arbitrary. The decimal point is convenient, however, because in many bill sheets there is provided a line separating the dollars and cents. If it is assumed that 110 the point on the work-sheet where it is desired to locate the decimal point is indicated, one method of operating the device to properly position the tappet would be to 115 merely shift the carriage until the decimal point position on the sheet comes to the printing point, as indicated in Fig. 1. The front scale 71 located on the frame of the typewriter can then be referred to with the aid of the indicating pointer 72 located on 120 the carriage, and in this instance the decimal point position will be shown to be located at "40" on the scale. With the carriage thus located, the tappet 39 is slid along 125 its supporting bar and dropped into the locating notch. The tappet thus located will be in proper position to cooperate with the jacks, so that the digits of the number as selected by said tappet will correspond in 130 denominational order with the digits as

printed in the particular column selected. After thus positioning the tappet, the carriage is, of course, moved to disengage the roller 67 from the notch 68 and to free it from the plate 69. The tappet thus freed drops to the proper position under the impulse of the frame 61, so that it may cooperate with the denominational jack corresponding to the first digit of the number 10 to be printed. In failing to its proper position, the pin 51 of the tappet will, of course, engage one of the notches 52, and the rib 55 will engage between the teeth of the rack 54, so that the tappet will be locked against 15 transverse movement when in position to select the denominational devices or jacks.

Another way of using the device is to swing the tappet up to a position slightly greater than that shown in Fig. 5, and in a 20 position lateral of the carriage, such that the tappet will be opposite the positioning notch 68. Then, while holding the tappet in this position, the typewriter carriage is moved to position the particular digit of 25 the column or the decimal point opposite the printing point. The tappet is then released and dropped into the notch 68. The remaining manipulation is the same as that described in the first example of the use of 30 the device.

A third method of using the device would be to set the tabulator stop at that point on the scale corresponding to the printing of the decimal point at the desired location 35 on the work-sheet. The tabulator key is then depressed to position the carriage in accordance with the tabulator stop which has been thus set. The tappet 39 is then slid along and dropped into the positioning 40 notch. The further procedure is the same as that indicated in the first described method of use of the device.

It will thus be seen that by using the finding notch, it is not necessary to try the position 45 of the tappet a number of times before it is properly located, and that any inexperienced person can bring the selecting tappet to a position corresponding to the position of the stop 19 and the location of the decimal point desired on the work-sheet. Of course, if the tappet 39 is located accurately 50 for the decimal point, it will be located for all other letter spaces of the particular computing zone, and thus for every denominational column of the zone, and will hence actuate the jacks 41 at the proper times to correspond with the printing of the same denominations on the work-sheet on the platen.

Variations may be resorted to within the 60 scope of the invention, and portions of the improvements may be used without others.

Having thus described my invention, I claim:

1. The combination with a typewriting

mechanism including a traveling carriage, 65 of a computing mechanism, a tappet carried by said carriage for causing the denomination being computed in and by said computing mechanism, with the denominational columns of said typewriting mechanism, 70 and a member fixed relatively to said carriage having a position-determining notch therein to receive said tappet and thereby locate said tappet on said carriage in a position such as to control the correspondence 75 of the computed denomination with the typewritten denomination of the zone at the printing point of said typewriting mechanism.

2. The combination with a typewriting 80 mechanism including a carriage and means for determining the position of said carriage for a given computing zone, of a computing mechanism, a tappet for causing the denominations being computed in and by 85 said computing mechanism with the denominational columns being printed by said typewriting mechanism, a series of denominational jacks connected to said computing mechanism and arranged to be operated 90 *seriatim* by said tappet, and a member convenient to said carriage and having a reference point corresponding to one of said jacks for properly locating said tappet on 95 said carriage to coöperate in proper sequence with all of said jacks.

3. The combination with a typewriting mechanism including a traveling carriage, of a computing mechanism, a tappet mounted on said carriage for causing the denominations being computed by said computing mechanism with the denominational columns being printed by said typewriting mechanism, a member arranged alongside said traveling carriage and fixed relatively thereto and having a notch therein, and a roller on said tappet arranged to engage said notch when said tappet is in a position to properly control the denominational columns of said computing mechanism for the computing 100 zone at the printing point of said typewriting mechanism.

4. The combination with a carriage, of a tappet pivotally mounted on said carriage, and means for returning said tappet to a 115 normally depressed position, said means having a considerable clearance with respect to said tappet when said tappet is in its lowermost position, admitting of a free upward movement of said tappet before engaging with said returning means.

5. The combination with a carriage, of a series of denominational members, a tappet on said carriage arranged to control the operation of said denominational members, 125 a pair of rods for supporting said tappet on said carriage, positioning means for locating said tappet properly on said carriage,

said tappet having a swinging movement about one of said rods, and relatively to the other of said rods, locking means connecting said tappet to one of said rods, and permitting a limited minor swing of said tappet relatively thereto while maintaining a locking engagement therewith so as to permit the actuation of said denominational members by said tappet while maintaining said 10 tappet locked against transverse movement, and locking means connecting said tappet with the other of said rods, permitting a major swing of said tappet wherein said tappet is unlocked from one rod, and maintained in locking engagement with the other rod, so as to permit a co-operation of said tappet with said positioning means, while maintaining said tappet in locked engagement against transverse movement with one 20 of said rods.

6. In a combined typewriting and computing machine, the combination with typewriting mechanism including a traveling carriage having a scale thereon, of computing mechanism, a tappet for selecting denominations, and means enabling said tappet to be positioned to cause the denominations computed to agree with the denominational columns printed by said typewriting mechanism, said means including a position locator with which said tappet may co-act in any position of the typewriter carriage.

7. In a combined typewriting and computing machine, the combination with typewriting mechanism including a traveling carriage and a scale carried thereby, of tabulating mechanism to determine the position of said carriage for a computing zone, computing mechanism, a tappet carried by said carriage for selecting the denominations of said computing mechanism, and means for causing the denominations selected by said tappet to agree with the denominational columns being printed by said computing mechanism, said means including a position locator with which said tappet may co-act to position said tappet to correspond with the denominational orders 50 of the column selected by said tabulating mechanism.

8. In a combined typewriting and computing machine, the combination with typewriting mechanism including a carriage, of computing mechanism, denominational selecting devices therefor, a tappet to co-operate with said denominational devices, said tappet mounted on said carriage and adjustable therealong, to cause the denominational selection to agree with the position of the numbers in the column written by said typewriting mechanism, said tappet being pivotally mounted, means for securing said tappet against later movement in its normal

position, said tappet being movable out of engagement with the securing means for the purpose of adjustment laterally, and means universal to all positions of said tappet for returning said tappet to normal position, whereby it may co-act with said denominational selecting devices and with said securing means.

9. In a combined typewriting and computing machine, the combination with a typewriter carriage, of computing mechanism, denominational selecting devices, a tappet for co-acting with said denominational devices, said tappet being normally in a position out of contact with said denominational devices, a support for said tappet comprising a bar mounted on said carriage, said tappet being pivotally and slidably mounted on said bar, a universal frame pivotally mounted on said bar, spring means for holding said frame in normal 85 position and yielding under a pressure of said tappet to admit of the raising of said tappet to an abnormal position, whereby said tappet may be moved laterally and out of contact with said denominational devices 90 for the purpose of positioning it to select different columns as printed, said frame acting to return said tappet to normal position, and a step for holding said frame clear of said tappet when both said frame and 95 said tappet are in their normal positions to admit of a certain amount of free play of said tappet, so that the same may be moved into engagement with said denominational selecting devices. 100

10. In a combined typewriting and computing machine, the combination with a typewriter carriage, computing mechanism, denominational selecting devices for said computing mechanism, and a tappet co-operating with said devices, of a support for said tappet comprising a pair of bars mounted on said carriage, said tappet having a locking engagement with both said bars when in working position to engage 105 said denominational devices, said tappet being pivotally mounted so as to swing to a position clear of both of the locking means 110 to enable said tappet to be adjusted to different column positions. 115

11. In a combined typewriting and computing machine, the combination with a typewriter carriage, computing mechanism, denominational selecting devices for said computing mechanism, and a tappet to co-operate with said denominational devices; of a support for said tappet comprising a pair of bars on said carriage, each of said bars having teeth formed therein, a pin on said tappet engaging the teeth of one of said bars, a rib on said tappet engaging between the teeth of the other of said bars, both said pin and said rib acting to hold said tappet 120 125

against lateral movement when said tappet is in position to engage said denominational selecting devices, said tappet being arranged to swing to a position whereby said pin is disengaged from the teeth of said bar, so that said tappet may then be moved to different lateral positions to coöperate with

said denominational selecting devices in different columns to agree with the columns as printed by the typewriting mechanism.
